UNITED STATES PATENT OFFICE.

JOSEPH SCOTT BENSON, OF IOWA CITY, IOWA.

GAS-ENGINE.

No. 879,726.

Specification of Letters Patent.

Patented Feb. 18, 1908.

Application filed August 2, 1907. Serial No. 386,852.

To all whom it may concern:

Be it known that I, JOSEPH SCOTT BENSON, a citizen of the United States, residing at Iowa City, in the county of Johnson and State of Iowa, have invented a new and useful Gas-Engine, of which the following is a specification.

This invention relates to internal combustion engines, and has for its principal object to provide a novel form of engine in which provision is made for effecting the introduction of an explosive charge at every second stroke of the piston, that is to say, once during each revolution of the crank shaft, as in a two cycle engine, or once during each two strokes of the crank shaft as in a four cycle engine.

A further object of the invention is to provide an engine of this type in which the change from two cycle to four cycle type, or from four cycle to two cycle may be instantly made, so as to be available in case of emergency, as, for instance, in the driving of an automobile or launch, where the two cycle type may be made available for sudden spurts, while the engine may be ordinarily run four cycle in order to economize in fuel.

With these and other objects in view, as will more fully hereinafter appear, the invention consists in certain novel features of construction and arrangement of parts, herein-after fully described, illustrated in the accompanying drawings, and particularly pointed out in the appended claims, it being understood that various changes in the form, proportions, size and minor details of the structure may be made without departing from the spirit or sacrificing any of the advantages of the invention.

40 In the accompanying drawings: Figure 1 is a sectional elevation of an internal combustion engine constructed in accordance with the invention. Fig. 2 is a side elevation of the same, partly in section.

45 Similar numerals of reference are employed to indicate corresponding parts throughout the several figures of the drawings.

The engine includes a base 10 and crank case 11, these being of any desired construction, and the crank case being provided, as usual, with bearings for the support of the crank shaft 12.

Above the crank case is a cylinder 15 which communicates with the crank case by means of a transfer port 16, as in the two cycle en-

gine, and opposite the cylinder end of the transfer port is an exhaust port 17.

The explosive charge is drawn into the crank case through an inlet port 18 leading from a carburetor or other suitable source of supply.

Arranged within the cylinder is a piston 20 that is connected in the usual manner to the crank shaft 12, and mounted on the crank shaft is a pinion 22 that intermeshes with a gear 23 on the half time shaft 24 in the manner usual in four cycle engines.

Arranged in the transfer port is a rocker valve 30 having a port 31 which may be moved to open or close the transfer port. Projecting from the stem 32 of this valve is an arm 23', the outer end of which is connected to a vertically disposed rod 35, the lower end of which is guided in a bearing formed in a bracket 36 that projects from the cylinder.

Surrounding the stem 32 is a torsion spring 37 that tends to maintain the valve in closed position and which serves to effect the closing movement after each upward movement of the rod 35. Extending from the rod 35 is a pin 40 which may be engaged by a cam lever 41 for the purpose of raising the rod 35 and holding the same up against the stress of the spring, so that the valve may be maintained in open position.

Pivoted at one side of the crank casing is a lever 43 one end of which acts as a tappet for raising the rod 35. The opposite arm of the lever is provided with an elongated slot 90 for the reception of a pin 45 that projects from a disk 46 on the shaft 24 the arrangement being such that when the engine is operating after the manner of a four cycle engine the valve will be opened once during each two revolutions of the crank shaft. When the parts are in the position shown in Fig. 1 the valve 30 is closed and the exploded charge is escaping through the port 17. During the next upward movement of the piston, the valve will remain closed and near the completion of the next movement in the direction of the crank shaft the valve will be opened, so that a charge may enter the cylinder and be compressed on the next out stroke of the piston, the operation being similar to that of the four cycle engine, with the exception that the exhaust port is located at the crank shaft end of the cylinder instead of at the opposite end thereof.

When the device is to operate as a two cycle engine it is merely necessary to hook up the rod 35 which may be accomplished by moving the cam lever 41, and this may be done by a foot lever or hand lever arranged within convenient reach of the engineer. This moves the valve to open position and the operation thereafter will be similar to that of a two cycle engine. When 10 the rod 35 is moved up, it is preferably moved a distance sufficient to place it beyond the reach of the lever 43, so that the latter will run idle.

Provision is also made for changing the 15 spark when the type of engine is altered.

I claim:

1. In an internal combustion engine, a cylinder, a crank casing, a transfer port for conveying an explosive charge from the 20 crank casing to the cylinder, a rocker valve arranged in said port, a half time shaft, a valve actuating means operable from said shaft and serving to move the valve to open position once during each two revolutions of 25 the crank shaft, and means for disconnecting the operating mechanism and locking said valve in open position to permit operation as a two cycle engine.

2. In an internal combustion engine, a cylinder, a crank case, a piston, a crank 30 shaft connected to the piston, an inlet port in communication with the crank case, a transfer port within the crank case of the cylinder, an exhaust port leading from the cylinder, a rocker valve mounted in the 35 transfer port and controlling the same, a rocker arm connected to the valve, a half time shaft geared to the crank shaft, a disk carried by the half time shaft and provided with a crank pin, a lever arranged to be engaged and operated by the crank pin, a rod connected to the rocker arm and arranged to be engaged by said lever to move the valve to open position once during each two revolutions of the crank shaft, a spring for moving the valve to closed position, and means for locking the rod out of contact with the lever and holding the valve in open position.

In testimony that I claim the foregoing as my own, I have hereto affixed my signature 50 in the presence of two witnesses.

JOSEPH SCOTT BENSON.
